UNITED STATES PATENT OFFICE.

HENRY C. BRINKER, OF INDIANAPOLIS, INDIANA.

CABINET.

953,457.

Specification of Letters Patent. Patented Mar. 29, 1910.

Application filed July 9, 1908. Serial No. 442,697.

To all whom it may concern:

Be it known that I, HENRY C. BRINKER, of Indianapolis, county of Marion, and State of Indiana, have invented a certain new and useful Cabinet; and I do hereby declare that the following is a full, clear, and exact description thereof, reference being had to the accompanying drawings, in which like numerals refer to like parts.

10 The object of this invention is to provide a cabinet containing drawers that when withdrawn are so mounted that they may be turned laterally and held in the turned position to render their contents accessible.

15 The invention has been applied practically to prescription cases for druggists, the drawers being adapted to contain bottles and the like but it may be used for other purposes. The invention gives to druggists and others 20 a cabinet of much greater capacity than the ordinary cases of shelving occupying the same wall space. In other words, without increasing the wall space, one can greatly increase the capacity of their means for 25 holding bottles and the like.

The invention also has the virtue of keeping the contents closed from dust.

Another feature of the invention consists 30 in providing a drawer open or partially open on one side so that when it is turned laterally, after being withdrawn, it will present all the bottles or contents therein to view and hold the same so as to be readily accessible.

35 The full nature of the invention will be understood from the accompanying drawings and the following description and claims.

In the drawings Figure 1 is a perspective 40 view of my cabinet with the drawers closed. Fig. 2 is the same with drawers partially open and some of them turned laterally. Fig. 3 is a front elevation of a drawer closed and the surrounding casing partly broken 45 away. Fig. 4 is a vertical section through the cabinet on the line 4-4 of Fig. 3 showing the drawer closed. Fig. 5 is a section similar to that shown in Fig. 4 with the drawer open and turned laterally. Fig. 6 is 50 a section on the line 6-6 of Fig. 3. Fig. 7 is a section on the line 7-7 of Fig. 6. Fig. 8 is a horizontal section on the line 8-8 of Fig. 6, the different positions of the drawer while being turned laterally being shown by 55 dotted lines. Fig. 9 is a section on the line

9-9 of Fig. 7. Fig. 10 is a section on the line 10-10 of Fig. 9.

As shown in the drawings, 10 represents the casing of the cabinet provided with vertical partitions 11 and horizontal partitions 12 that form recesses for drawers 13. 60

The drawers herein shown have, besides the front wall thereof, a rear wall 14, a top wall 15, a bottom 16, a horizontal partition 17 midway between the top and the bottom, one side wall 18 that extends from top to bottom and the slats or bars 19 that extend across one side at points slightly above the bottom 16 and the partition 17. 65 These slats 19 are for the purpose of preventing the bottles, boxes and the like from falling out when the drawer is in its open position. The drawer is adapted to contain bottles 20 and boxes 21 or any other thing, as indicated in Fig. 4 where the 70 drawer is shown closed. The front has a handle 22 for handling it.

The drawer is guided in the movements into and out of the recess by a pair of angular guide strips 25 secured to the stationary 75 parts forming the recess at each corner thereof, and strips 26 that are located so as to slide between the strips 25. Each strip 25 has an overlapping extension or flange 126 that rides and slides upon an 80 inwardly extending flange 125 on each strip 25, as shown in Fig. 7. The drawer is pivotally connected at the top and bottom with said strips 26 by the means shown in 85 Fig. 9. A pin 27 passes through the bottom and also another through the top of the drawer and is externally barbed or roughened and forced tightly into the sleeve 28 in the slots 29 of the slides 26. This connection between the drawer and 90 the slides 26 is located midway of said parts. When the drawer is withdrawn it will pull the slide out, as indicated in dotted lines 95 in Fig. 8, until the drawer is out of the recess or the movement of the slide is 100 stopped by the pin 30 that is secured to the horizontal partition 12 of the casing and projects into the slot 31 in the slide. Then the drawer, which is centrally fulcrumed on the slide between the slots at the bottom 105 and top thereof, is turned laterally into the dotted line position shown in Fig. 8 and then pushed inwardly to the full line position shown in Fig. 8 so that the drawer extends crosswise of the front of the cabinet 110

and lies against the unopened drawers on each side.

In the open position the open side of the drawer is exposed to the front and, therefore, the druggist can easily obtain any package or bottle therein and replace the same in the position from which they were removed without any difficulty or confusion. The drawer is returned by reversing the opening operation, that is, it is pulled forwardly from the full line position and then turned 45 degrees and pushed inwardly. The slides 26 are so wide as to furnish a very substantial and broad support for the drawers when in their outer position and since they are held there by the connection shown in Fig. 9, the drawers can not escape from the slides and the slides can not escape from the guideway in the cabinet by reason of the stops 30 and the guide-strips on each side of the slides. Where light articles are to be used in the cabinet only the bottom slide construction is necessary as that will satisfactorily guide and hold the drawer, but when the contents are relatively heavy there should be a guide construction at both the top and bottom of the drawer. Therefore, it is obvious that the drawers may be the double compartments shown in Figs. 4 and 6 or the single compartments as shown in Fig. 2, as one's need requires. Such a cabinet may be made relatively deep for when the drawer is withdrawn and turned laterally it lies against the front part of the casing and drawers so that it is partially braced thereby and quite a long drawer may be maintained stably in position.

What I claim as my invention and desire to secure by Letters Patent is:

46 1. A cabinet including a casing having drawer recesses, a drawer in each recess, means under each drawer for supporting the same in both its inner and outer positions, and a pivotal connection between said drawer and said support that permits the drawer to be slidable inwardly or outwardly on said support and to be turned laterally and held thereon when in its outer position.

50 2. A cabinet including a casing with a drawer recess therein, a drawer support slideable in said recess, and a pivotal connection between said drawer and drawer support that permits the drawer to slide longitudinally of said drawer support and to be turned laterally and held thereon when in its outer position.

55 3. A cabinet including a casing with a drawer recess therein, a drawer support slideable in said recess and having a longitudinal slot therein, a drawer on said support, a fulcrum pin projecting from said drawer into said slot so that the drawer may be drawn outwardly and turned laterally on said support and be supported thereby in

such position, and a stop for limiting the outward movement of the drawer support.

4. A cabinet including a casing with a drawer recess therein, a drawer, a support slideable in said recess of the casing upon which said drawer is fulcrumed in a slot so that it may be turned laterally in connection with said sliding supports and be supported thereby in such position, said support being provided with a longitudinal stop slot and a pin stationary in the cabinet projecting into said slot for preventing the escape of said support from the recess.

5. A cabinet including a casing with a drawer recess therein, a drawer, and supports slideable in the bottom and in the top of said recess of the casing upon which said drawer is centrally fulcrumed at its top and bottom so that it may be turned laterally in connection with said sliding supports and be supported thereby in such position.

6. A cabinet including a casing with a drawer recess therein, a guide strip secured at each of the four corners of said recess, each guide strip having an inwardly extending flange along the lower part of said guide strip, a drawer support slideable between said guide strips and upon the ledges thereof, each support having a pair of longitudinal slots, stop pins secured at the bottom and top of the recess that project into one groove in each support, and a fulcrum extending vertically from the top of said drawer into the slots of said supports, substantially as set forth.

7. A cabinet including a casing with a drawer recess therein, a drawer, and a support adapted to project forwardly beyond the casing, one of said last two members being longitudinally slotted and the other provided with a pin projecting into said slot whereby the drawer will be supported in its outward position by said support so that the drawer may be turned laterally.

8. A cabinet including a casing with a drawer recess therein, a drawer with its ends, top and bottom and one side closed and the other side open to render the contents accessible when the drawer is drawn outwardly, a bar across said open side to hold the contents from falling out when the drawer is drawn outwardly, and a support slideable in said recess of the casing upon which said drawer is fulcrumed centrally so that it may be turned laterally in connection with said sliding supports and be supported thereby in such position.

In witness whereof, I have hereunto affixed my signature in the presence of the witnesses herein named.

HENRY C. BRINKER.
